United States Patent Office.

ISRAEL LANCASTER, OF BALTIMORE, MARYLAND.

Letters Patent No. 75,774, dated March 24, 1868.

IMPROVEMENT IN HARVESTERS.

The Schedule referred to in these Letters Patent and making part of the same.

Be it known that I, ISRAEL LANCASTER, of Baltimore, in the county of Baltimore, and State of Maryland, have invented a new and useful Improvement in Reaping or Harvesting-Machines; and I do hereby declare that the following is a full, clear, and exact description of the construction and operation of the same; reference being had to the annexed drawings, making a part of this specification, in which—

Figure 1 is an elevation of the driving-wheel and the reciprocating lever, which lever is shown in longitudinal section.

Figure 2 is an elevation of the driving-wheel shaft, showing the position of the driving-wheel, reciprocating lever, and tightening-nuts upon it.

In that class of reaping-machines in which the cutting-bar is driven by means of a succession of short cams placed in the side or circumference of the master-wheel, there is an objection arising from the lost motion, between the cams and the roller, the different bearings, and the vibration of the frame. As great rapidity of stroke is required, amounting to eight hundred per minute, the cam movement ceases to be a cam movement, but resembles a succession of strokes made with a hammer, the cutting-bar being knocked from one extremity of the stroke to the other, causing an excessive jarring of the whole machine, and a waste of one-half of the whole power required to drive the cutting-bar, as experiment shows.

This rough movement has prevented the use of this quality of machine almost entirely, although much more simple in its construction than those generally in use.

I overcome this difficulty, effectually preventing any lost motion whatever, as follows:

A, fig. 1, is the driving-wheel, containing a succession of short cams, placed in the side, at or near the circumference. These cams are seen at O, which is a representation of the band, tire, or tread of the wheel, extended in a straight line. L is the shaft; F, the pivot-block; E, the fulcrum-block, forming a part of the reciprocating lever D D; g g are pins passing through the fulcrum-block E, and securely fastened into the pivot-block F; c c' are friction-rollers, placed on the lever D D, and working on the face of the cams n n n n; B is the cutting-bar, through an eye in the shank of which the lever D D passes. An odd number of cams is placed on the wheel, so that when the roller c' is on the point p, the roller c is in the depressed part S. As the driving-wheel revolves, the movement of the cutting-bar is obvious. At Figure 2, L is the shaft, m m the journals for bearings, A the driving-wheel, E the fulcrum-block, D the reciprocating lever, g g the fulcrum-pins; K and H are nuts working on a screw-thread cut in the shaft. The nut H is screwed against the pivot-block F, fig. 1, holding the lever D D in position, with the rollers c c' pressing against the face of the cams n n n n. The required amount of pressure is given by operating the nut H, as also any wearing away of parts is remedied by moving this nut. k is the tightening-nut, holding the mechanism securely in place, by being screwed firmly on the nut H.

The cutting-bar can be thrown out of gear by turning back the nuts K and H until the rollers c c' are removed from the track of the cams.

What I claim as my invention, and desire to secure by Letters Patent, is—

The method of holding the reciprocating lever D D up to its work, by means of nuts screwing on the driving-wheel shaft, substantially as described.

I. LANCASTER.
